UNITED STATES PATENT OFFICE.

AARON WALKER, OF KOKOMO, INDIANA.

FIRE-ESCAPE.

SPECIFICATION forming part of Letters Patent No. 295,313, dated March 18, 1884.

Application filed January 24, 1884. (No model.)

To all whom it may concern:

Be it known that I, AARON WALKER, a citizen of the United States, residing at Kokomo, in the county of Howard and State of Indiana, 5 have invented certain new and useful Improvements in Fire-Escapes, of which the following is a description.

Figure 1 is a front elevation, with the hood or housing for the windlass in section; and 10 Fig. 2 is an end elevation, with the hood in section.

My invention relates to certain improvements upon that form of fire-escape in which a swinging balcony is suspended from a windlass at 15 the top of the house, and is raised and lowered by means of ropes and pulleys. It relates more particularly to my own patent granted September 4, 1883, No. 284,517, in which the balcony is suspended in the bight or loop of a rope, 20 one end of which connects with a large drum of a differential windlass on one side, and the other end of which connects with a small drum on the opposite side. With this differential windlass I find that the weight of 25 the balcony exerts a greater leverage on the larger drum of the windlass, and in unwinding the latter against the small drum allows the balcony to descend.

My present invention consists in combining 30 with such a windlass one or more ropes, pulleys, and weights, that oppose the unwinding of the large drum and the winding up of the small drum, whereby the balcony is balanced and remains stationary at any desired point.

35 The invention also consists in the peculiar arrangement of guide-bars to keep the ropes in place, and in other details of construction, as hereinafter more fully described.

In the drawings, A represents the front of 40 the building, at the upper portion of which, near the roof, is arranged the differential windlass mounted in bearings in brackets B B'. This windlass is covered and protected from the weather by a hood or housing, C, which may 45 be permanently fixed in place or detachably fastened by means of hooks and staples, as shown.

Instead of one pair of differential drums, as 50 in my former patent, I employ two pairs, D D' and E E', and two ropes, D² and E², and two pulleys, D³ E³, fixed to the balcony F, and suspended in the bights or loops of the two ropes.

By duplicating these drums, ropes, and pulleys, and placing one set at each end of the balcony, I cause the latter to be more steadily 55 suspended, and dispense entirely with the side guides for the balcony, as shown in my prior patent.

Near the middle of the windlass there are two drums, G G', upon which are wound two 60 ropes, H H'. One of these ropes, H, descends to and is wound around a pulley, I, on the balcony, which is provided with a crank, a, a ratchet-wheel, b, and a pawl, c, and the other rope passes through an eye, d, Fig. 2, 65 in the hood, and extends to the ground. The rope H', extending to the balcony, affords means for winding up the windlass and balcony by the persons on the balcony, and serves also as a brake or regulator in the hands of 70 the persons on the balcony, to regulate the descent of the same by taking hold of the crank and slowly unwinding it.

To stop and lock the balcony at any given point, the pawl c is thrown into engagement 75 with the ratchet-wheel b. The other rope, H, which extends to the ground, affords means for raising or lowering the balcony from the ground in a similar manner. Now, in the connection of the two ends of each of the ropes 80 D² E² to the windlass, it will be seen that one end of each connects with a large drum, D or E, and the other end with the smaller drum, D' or E', and as the weight of the balcony strains equally upon both sides of each rope, 85 and the ropes on the larger drum exert a greater leverage and winding strain on the windlass than the ropes on the smaller drum, it will be seen that the larger drum will unwind and wind up the smaller drum when a 90 sufficient weight is on the balcony. To counteract this I construct pulleys or drums J J' 95 on the ends of the windlass and provide ropes K K' and weights L L' for them, which ropes pass around the pulleys, while the weights are fastened to pull upon the opposite side of the pulleys from the connection of the cord D² on the larger drums. The ends of these ropes may either be attached to the balcony or be simply wound around and fastened to the wind- 100 lass. The function of these cords and weights is to neutralize the difference of strain of the two ends of the rope in their attachment to the two drums by resisting the turn of the larger

drums and co-operating with the turn of the smaller drum.

M M' are two rods, which extend horizontally the full length of the balcony, and are then 5 bent down and connected to the hand-rail and floor at each end. These two rods are arranged parallel to each other and close together, and between them pass all of the ropes running to the balcony. These rods serve as guides to 10 keep the ropes in place and act to some extent as brakes as the ropes pass between them. They furthermore render the balcony stiffer and less liable to tip or turn about its points of suspension.

15 N N are cushion-strips, of rubber or other soft material, arranged at the ends of the balcony on the sides next to the wall, to prevent bruising the balcony or the wall.

O is a gate in the hand-rail of the balcony, 20 by which ingress and egress to or from the balcony is had when the balcony is on the ground.

P are openings in the wall of the balcony, next to the building, through which access may be had to the balcony from the windows of 25 the building. These openings are provided with sliding doors Q for closing the same.

Having thus described my invention, what I claim as new is—

1. The combination, with a windlass having 30 differential drums, ropes attached to said drums, and a balcony hung in the bight or loop of the rope, of a counter-weight and rope, arranged as described, to oppose the unwind-

ing of the larger drum, as and for the purpose described.

2. The combination, with the differential windlass having drums of different diameters, and one or more suspending-ropes for the balcony, of a drum, G', rigidly connected to the windlass, the rope H', the pulley I on the 40 balcony, with crank a, ratchet-wheel b, and pawl c, as and for the purpose described.

3. The combination, with the differential windlass having differential drums D D' and E E', and drums G G', arranged between them and 45 working rigidly with the windlass, of the balcony having pulleys D' E', the two suspending-ropes D' E', and the two working-ropes H H', one of the same being extended to the ground, and the other wound about a crank-pulley on 50 the balcony, as and for the purpose described.

4. The combination, with a windlass, a balcony, and suspending-ropes, of the two horizontal guide-rods M M', inclosing the ropes between them, and rendering the balcony stiff 55 against tipping or rocking about its point of suspension, as described.

5. A fire-escape balcony provided with elastic cushions or buffers on its side next to the wall, in combination with hoisting-ropes and 60 a windlass, as and for the purpose described.

AARON WALKER.
